UNITED STATES PATENT OFFICE.

EMIL MUNDORF, OF AACHEN, GERMANY.

FULLED WOVEN FABRIC.

Application filed May 6, 1925, Serial No. 28,490, and in Germany May 20, 1924.

In the ordinary fulled fabrics with rectangularly crossing warp and weft threads, the warp threads extend in the longitudinal direction and the weft threads in the transverse direction of the fabric. The same is the case in garments and other articles made of such fabrics. If this fabric or articles made thereof are submitted to tensile stresses in the longitudinal direction, it will only be the warp threads which will oppose resistance to the stresses, while the weft threads remain entirely inactive. It will be inverse if the fabric is placed under stress in the transverse direction.

15 The invention has for its object to provide a fulled woven fabric in which the rectangularly crossing warp and weft threads extend diagonally with relation to the edges of the fabric.

20 In the accompanying drawing Figs. 1 and 2 illustrate, by way of example, a mode of manufacturing a fabric according to the present invention.

In a manner known per se, the fabric is first woven in the form of a tube *a*, Fig. 1, in which the warp threads extend longitudinally and the weft threads transversely. The tube thus formed is then cut up along a helical line *b* into a simple web of fabric *c*, shown in Fig. 2. As will be seen from the last-said figure, the warp and weft threads while crossing rectangularly extend diagonally with relation to the edges of the fabric. A fulled fabric according to the present invention possesses numerous advantages over the ordinary fulled fabrics in which the warp threads extend in the longitudinal and the weft threads in the transverse direction. The present fabric is very ductile both in the longitudinal and transverse direction, i. e. in the directions in which garments made of the fabric are submitted to tensile stress. Besides, in making garments, covers, etc. of the fabric the edges need not be provided with seams but they can remain open even if the fabric is made of cheap raw materials such as, for instance, of shoddy. Since the warp and weft threads form an acute angle

with the fabric edges so that no thread extends parallelly of the same, the felting of the threads obtained by the fulling operation keeps the threads together in such a manner as to render impossible a feazing of the edges. The present fabric further has a greater tensile strength than the old fabrics because any longitudinal and transverse stresses are taken up by the warp and weft threads in common. Therefore, raw materials of comparatively minor quality may be used for manufacturing a cloth of definite strength.

As the fabric is yieldable in two directions, garments made from the same will fit better than garments of the ordinary fabric.

Owing to the greater strength or resistibility of the fabric in the directions in which the tensile stresses are mostly exerted, it can be made of less threads per unit of area than the garment cloth used hitherto. Thereby, the cloth becomes cheaper and lighter, while nevertheless a high density and insulative property may be imparted to it by an efficient raising and fulling operation.

Having thus described my invention, what I claim as new and desire to secure by Letters-Patent, is:—

1. A method of producing a fulled woven fabric, consisting in weaving the fabric in tubular form, cutting said fabric tube along a helical line to provide a web of fabric in which the rectangular crossing warp and weft threads extend diagonally with relation to the longitudinal edges of the fabric and finishing the fabric to full the same whereby in the fulling operation the warp and weft threads are equally engaged by the finishing instruments.

2. As a new product, a fulled woven fabric in which the crossing warp and weft threads extend diagonally to the respective edges of the fabric.

In testimony whereof I have signed my name to this specification.

EMIL MUNDORF.
